UNITED STATES PATENT OFFICE

CARL F. WOLTERS, OF MARIETTA, OHIO

DESIGN FOR A COMBINED CONCENTRIC DIAL PLATE, LOCK DIAL AND HANDLE FOR
SAFES

Application filed April 20, 1931. Serial No. 39,555. Term of patent 7 years.

To all whom it may concern:

Be it known that I, CARL F. WOLTERS, a citizen of the United States, residing at Marietta, in the county of Washington, and State of Ohio, have invented a new, original, and ornamental Design for Combined Concentric Dial Plate, Lock Dial and Handle for Safes, of which the following is a specification, reference being had to the accompanying drawings, forming part thereof.

Fig. 1 is a front elevation of a combined

concentric dial plate, lock dial and handle for safes, showing my new design.

Fig. 2 is a side elevation of the combined concentric dial plate, lock dial and handle shown in Fig. 1.

I claim:

The ornamental design for a combined concentric dial plate, lock dial and handle for safes, as shown.

CARL F. WOLTERS.
